DESIGN FOR A BOTTLE

José de Miguel Vicent, Mexico, D. F., Mexico, assignor to Jose Junco Blanco, Mexico, D. F., Mexico

Application December 16, 1940, Serial No. 97,394

Term of patent 14 years

To all whom it may concern:

Be it known that I, José de Miguel Vicent, a citizen of the Republic of Mexico, residing at Mexico, D. F., have invented a new, original, and ornamental Design for a Bottle, of which the following is a specification, reference being had to the accompanying drawing, forming part thereof.

I claim:

The ornamental design for a bottle, as herein shown.

JOSÉ DE MIGUEL VICENT.
